CLAIM

The ornamental design for a vehicle bumper, as shown and described.

DESCRIPTION

FIG. 1 is a front perspective view of a vehicle bumper attached to a vehicle, no part of the vehicle is claimed;

FIG. 2 is a front view of the vehicle bumper;

FIG. 3 is a left perspective view of the vehicle bumper;

FIG. 4 is a left side view of the vehicle bumper;

FIG. 5 is a right side view of the vehicle bumper;

FIG. 6 is an enlarged fragmental front view of the area marked 6 in FIG. 2;

FIG. 7 is a top plan view of the vehicle bumper; and,

FIG. 8 is a right perspective view of the vehicle bumper.

The broken lines are for illustrative purposes only and form no part of the claimed design.

The stippling indicates the curvature of the front fascia. The front fascia has an in-board upper curved portion descending below the generally upper line of the front fascia receiving a portion of a headlight.
